ABSTRACT

The winding and setting stem of a calendar watch has a pushed-in winding position and a pulled-out time setting position. In the pushed-in position, rotation of the stem is transmitted by a crown wheel which moves for one direction of rotation into a barrel-winding position and for the opposite direction of rotation into a position in which it drives a heart to advance a date-ring step-by-step. A sprung hammer tends to keep the heart in a disengaged position and prevents unwanted setting of the date.

2 Claims, 4 Drawing Figures

FIG. 1FIG. 3

FIG. 4

DATE SETTING DEVICE OF A CALENDAR WATCH

BACKGROUND OF THE INVENTION

The invention relates to watches, and is particularly concerned with devices for setting the date indication of a calendar watch by rotation of a winding and setting stem.

An object of the invention is thus to improve a date-indicating watch of the type including a rotatable winding and setting stem having at least two distinct axial positions including a pushed-in winding position and a pulled-out time setting position, a winding train, and a date ring.

SUMMARY OF THE INVENTION

The improvement provided by the invention comprises means for operatively connecting the stem in said pushed-in position to the winding train in response to rotation of the stem in one direction and to the date ring in response to rotation of the stem in the opposite direction.

BRIEF DESCRIPTION OF THE DRAWINGS

An embodiment of the invention will now be described, by way of example, with reference to the accompanying drawings, in which:

FIG. 1 is a rear elevational view of part of a watch according to the invention, shown in a winding position;

FIG. 2 is a view similar to FIG. 1, but shown in a date-setting position;

FIG. 3 is a front elevational view of part of the watch of FIG. 1; and

FIG. 4 is a cross-section taken along line IV—IV of FIG. 2.

DESCRIPTION OF THE PREFERRED EMBODIMENT

The device shown in the drawing is intended for the rapid setting of date indications carried by a date-ring 1 (FIGS. 3 and 4) by the rotation of a winding stem 2 in the direction opposite to that for winding. As schematically shown in FIGS. 1, 2 and 4, the stem 2 drives a winding pinion 3 which in turn drives a crown wheel 4. The crown wheel 4 is mounted on a non-circular hub 5 provided integral with and upstanding from bridge 9 and on which crown wheel 4 may be laterally displaced and turn. The hub 5 has a smooth lateral surface formed by two similar circular segments 5a and 5b whose radii are equal to the radius of a circular opening 4a of crown wheel 4.

When the stem 2 is turned in the direction of arrow A (FIG. 1) which is that for winding, the opening 4a of wheel 4 bears on segment 5a of the hub 5 and in laterally displaced into driving engagement with a ratchet wheel 6 which is mounted on a square of arbor 6a of a winding barrel (not shown), whereby the barrel spring is wound.

When the stem 2 is turned in the direction of arrow B (FIG. 2), i.e., opposite to the direction for winding, the wheel 4 driven by winding pinion 3 leaves wheel 6 and is laterally displaced into driving engagement with a date correcting pinion 7, the opening 4a of wheel 4 bearing on the segment 5b of hub 5.

As shown in FIGS. 3 and 4, the date setting mechanism includes a shaft 8 pivotally mounted between bottom plate 10 and bridge 9; the pinion 7 is mounted on

a square at one end of shaft 8 and is held by a screw 11. At the other end of shaft 8 is fixed a corrector 12 having a lug 13 which, upon rotation of the shaft 8 by one turn, drives a tooth 1a of the date-ring 1 by one step.

As shown, the corrector 12 preferably has the form of a heart which, under the effect of a sprung hammer 14, normally holds the lug 13 in an inoperative position out of the trajectory of the teeth 1a of date-ring 1. This sprung hammer 14 also obliges the user to exert a fairly considerable force to carry out setting of the date, so that setting of the date cannot take place unintentionally.

The date-indicating calendar watch incorporating the described device may be provided with a winding stem

2 having two axial positions, a pushed-in one for winding and setting of the date, and a pulled-out one for setting of the time. It may also be provided with a winding stem having three axial positions: a pushed-in winding and date setting position, an intermediate position, and a pulled-out time-setting position, the intermediate position being reserved for the setting of a supplementary member, such as a day-star, an indicator for the time of ringing of an alarm, of a device for setting an hour hand in steps of one hour, upon a change of time zone, for example.

The described embodiment may be conceived differently. For example, the crown wheel 4 could be fixed against lateral displacement and simultaneously mesh with wheels 6 and 7 which act via respective one-way driving means such as inverted breguets, to drive the barrel arbor when the stem is turned in the winding direction and the date-ring when it is turned in the opposite direction.

The described device is simple and enables an easy setting of the date with a two-position winding stem. This is specially advantageous in an automatically wound watch where the necessity of manually winding is extremely rare.

What is claimed is:

1. A date-indicating watch comprising; a rotatable winding and setting stem having at least two distinct axial positions including a pushed-in position and a pulled-out position; a winding train; a date ring; a date-setting wheel connected with the date ring to set the same; a rotatable crown wheel operatively connected with the stem for rotation in a direction corresponding to the direction of rotation of the stem; and means for operatively connecting the stem by the crown wheel, in said pushed-in position of the stem, to the winding train in response to rotation of the stem in said one direction and to the date-setting wheel in response to rotation of the stem in the opposite direction, comprising means for mounting the crown wheel for lateral displacement to a first position meshing with the winding train in response to rotation of the crown wheel in said one direction and to a second position meshing with the date-setting wheel in response to rotation of the crown wheel in the opposite direction, said mounting means including a hub having two opposite like circular segments defined by intersecting circles of given radius, and said crown wheel having an inner circular bearing surface whose radius is equal to said given radius, said bearing surface selectively

bearing against said segments according to the direction of rotation of the crown wheel.

2. A date-indicating watch, comprising;

a rotatable winding and setting stem having at least two distinct axial positions including a pushed-in 5 position and a pulled-out position;

a winding train;

a date-setting wheel;

means, comprising a rotatable crown wheel, for operatively connecting the stem in said pushed-in position to the winding train in response to rotation of the stem in one direction and to the date-setting wheel in response to rotation of the stem in the opposite direction, the crown wheel being mounted to selectively occupy a first position for meshing with 10 the winding train in response to rotation of the stem in one direction and a second position for meshing with 15 the date-setting wheel in response to rotation of the stem in the opposite direction;

crown wheel in said one direction and in a second position for meshing with the date-setting wheel in response to rotation of the crown wheel in the opposite direction;

a date ring having teeth to drive it;

a heart driven by the date-setting wheel and carrying a lug cooperating with the teeth of said date ring to advance the date ring by one tooth in response to a rotation of the heart; and

a sprung hammer acting on the heart to bias it towards an inoperative position with said lug disengaged from said teeth of the date ring and to oppose rotation of the heart in said opposite direction of the stem when in said pushed-in position to prevent unwanted setting of the date.
